UNITED STATES PATENT OFFICE.

LARS H. BERGMAN, OF CHICAGO, ILLINOIS, ASSIGNOR TO RAYMOND BROS. ENGINEERING CO., OF CHICAGO, ILLINOIS, A CORPORATION OF ILLINOIS.

APPARATUS FOR PULVERIZING AND FEEDING FUEL TO FURNACES.

Application filed April 17, 1924. Serial No. 707,308.

To all whom it may concern:

Be it known that I, LARS H. BERGMAN, a citizen of the United States, residing at Chicago, in the county of Cook and State 5 of Illinois, have invented certain new and useful Improvements in Apparatus for Pulverizing and Feeding Fuel to Furnaces, of which the following is a specification.

My invention relates to an apparatus for 10 pulverizing coal and feeding the same into a furnace, and the invention has for its general purpose to provide a new and improved apparatus whereby the coal, instead of being stored after pulverization and 15 withdrawn from the storage bin in the quantities required for feeding to the furnace, is carried directly by an air current from the mill to the furnace, the pulverization taking place in the mill being regulated so as to 20 meet the requirements of the furnace without excess.

The invention contemplates preferably the 25 operation of the mill at a constant speed and the regulation of output by control of the feed of the coal to the mill. With such an arrangement in view one of the specific 30 objects of the invention is to provide means whereby the air introduced into the pulverized coal, into the mill for example, is proportioned in quantity to the fuel so that a proper ratio between air and fuel is 35 maintained regardless of the rate at which the fuel is supplied to the mill.

A further object is to provide for decreasing 40 the velocity of the fuel stream as it enters the furnace. The transportation of the fuel in suspension necessitates an air current which, if not damped, will give the burner flames a higher velocity than is usually desirable.

A further object is to provide means operative to prevent back firing and explosion in the mill in case movement of fuel from the mill to the furnace is stopped.

45 The invention consists of the new and improved constructions, arrangements and devices, singly and in combination, shown in the drawings appended hereto and to be hereinafter described and claimed for carrying out the above stated objects and such other incidental objects as will be referred to in the following description of the preferred embodiment of the invention illustrated in the drawings.

In the drawings—

Fig. 1 is a side elevation with parts in section of a pulverized coal furnace and the means provided by my invention for pulverizing the coal and feeding the same directly into the furnace.

Fig. 2 is a vertical sectional view of one of the fuel nozzles and associated parts.

Fig. 3 is a cross sectional view on line 3—3 of Fig. 2.

Fig. 4 is a fragmentary plan view of the change speed mechanism for regulating the feed of the fuel to the mill.

Fig. 5 is a fragmentary side elevation of the mechanism for controlling the introduction of air into the mill.

Fig. 6 is a fragmentary plan view of a multiple fuel nozzle constructed in accordance with my invention.

Fig. 7 is a sectional plan on line 7—7 of Fig. 5, and

Fig. 8 is a fragmentary view, in elevation, of the feed conduit, illustrating the automatic protecting device for preventing back firing into the mill.

Referring first to Fig. 1, A designates a pulverized fuel burning furnace which may be of any preferred type. In the type of furnace shown, 10 is the ash pit, 11 the boiler tubes, 12 the steam dome and 13 the stack flue. Fuel and air are introduced through the front wall 14 of the furnace in a downward direction through a multiple nozzle structure B consisting, in the case shown, of three burners.

C is a pulverizing apparatus which is shown as a roller mill of the Raymond type in which the pulverization of the material takes place between a stationary bull ring 15 and a plurality of rollers 16 on pendant journals 17 supported by a spider 18 on a rotating shaft 19.

D is a feeding device of the sort common to mills of this type comprising a bin 20 and a rotary pocket feeder the shaft 21 of which is provided with a ratchet wheel 22. In the installation herein shown the ratchet 22 is driven by a pawl 23 carried by a crank and link mechanism 24 provided for oscillating the crank, which link mechanism is operated from a shaft 25. Shaft 25 has a pulley 26 for a belt 27 which extends around a pulley 28 driven by suitable gearing 28' from a shaft 29 driven from a variable speed

transmission (Fig. 4) to be hereinafter referred to.

6 E is a conduit leading from the top of mill C to a fan or blower F with the eduction pipe of which nozzle B is connected.

6 G (Fig. 8) is a mechanism interposed between the fan F and the nozzle B for preventing back firing in case the mill stops.

10 The central shaft 19 of the mill is geared within the mill to a shaft 30, driven from an electric motor 31 the armature shaft of which is provided with a pulley 32 connected by belt 33 with a pulley on shaft 30. Shaft 30 has fixed thereto a sprocket 34 connected by chain 35 with the driving sprocket 36 of a "Reeves" variable speed transmission, the driven sprocket of which is designated 37 and is connected by chain 38 with a sprocket on shaft 29, above referred to.

15 The "Reeves" variable speed transmission is of familiar construction and need not be described in detail; and, in fact, any other variable speed device of suitable construction might be used in place of it. By shifting the ends of levers 39, 40 of the speed changing device to and from each other by the manipulation of screw 41 the pulleys 42, 42 and 43, 43 are spread apart or brought closer together so as to vary the speed ratio

20 as between the driving sprocket 36 and the driven sprocket 37, and hence the rate of feed of coal to the mill.

25 Air enters the circular air drum 44 of the mill, from where it goes to the mill under bull ring 15 and rollers 16, through a casing 45 which is open at the top and is provided with one or more valves or dampers, the position of which is controlled from the variable speed transmission employed for

30 regulating the quantity of coal fed to the mill. In the drawings (see particularly Figs. 1, 5 and 7) I have shown two dampers 46, 47 provided with gudgeons 48, 49, 50 and 51 turning in bearings in the upper member 52 of casing 45. Gudgeons 49, 51 are provided with levers 53, 54 connected by a link 55, and, pinned to gudgeon 51, is a lever 56 to which is secured a weight 57. Lever 56 is connected by a two-part link

35 58 provided with a turn buckle 59 with one arm of a bell crank 60 which is pivoted to the frame 61 of the variable speed transmission. The lever 40 of the transmission mechanism bears against the other, upstanding, arm 62 of bell crank 60. As a result of this arrangement when the feed of coal to the mill is reduced, that is, when the forward ends of levers 39, 40 of the variable speed transmission are spread further apart and

40 the opposite ends brought closer together to slow down the rotation of the revoluble pocket feeder, lever 40 is moved to the right (Figs. 4 and 5) and the weight 57 moves dampers 46, 47 toward their closing positions. The reverse operation takes place

when the feed of fuel to the mill is increased.

Preferably the current of air and fuel is divided and fed into the furnace through a plurality of nozzle pipes terminating in 70 burners, although the invention contemplates the use of a single nozzle. The multiple nozzle shown in the drawings comprises three identical pipe sections 63 (Fig. 6) having the longitudinal configuration 75 shown in Fig. 2. Projecting into and extending through each of the pipe sections 63 is a tubular member 64 open at its upper end to the atmosphere and at its lower end to the furnace. The nozzle or burner extends through the front wall of the furnace as shown in Figs. 1 and 2. The tubular member 64 provides a core of induced or auxiliary air in the middle of the stream of primary air and fuel. The auxiliary air operates to reduce the velocity of the fuel stream and of the flame produced thereby. This is particularly desirable in the direct feeding system with which my present invention is concerned since the transportation 90 of the pulverized fuel in suspension from the blower to the furnace involves the use of an air current of a higher velocity than is desired at the point where the fuel enters the furnace. A high flame velocity is not 95 economical of fuel and tends to burn out and slag the boiler setting.

The nozzle pipes 63 are connected with a header casing 65, the latter communicating, 100 by the interposition of a conduit section 66, to be described, with the eduction pipe 67 of the fan F. The fan may be of any desired type and is shown as driven by an electric motor 68. Extending through the header casing 65 are a pair of vertical shafts 105 69 to which are secured, within the casing, deflecting vanes 70 and on their upper ends above the casing a pair of fingers 71 for setting the vanes to any desired positions within the range of their angular movements. By a proper adjustment of the vanes the single stream of air and fuel from fan F is divided vertically into the three streams which enter nozzle pipes 63. The division of the stream of fuel and air vertically insures uniformity in the ratio as between air and fuel in the divided streams. Ordinarily the lower portion of the air stream will carry more of the solids than the upper portion, hence the desirability of dividing the 115 main stream vertically instead of horizontally.

Extending through the upper portion of the conduit section 66 is a shaft 72 to which is fixed a valve 73 formed so that when in the position shown in dotted lines in Fig. 8 it will shut off casing 65 from the eduction pipe 67 of the fan. Shaft 72 has fixed to one end thereof, outside of section 66, an arm 74 carrying a weight 75, the arm being formed 125

with a downturned finger 76. Under normal operating conditions the valve 73 is held in the upper part of section 66 by a latch 77 fixed to a rock shaft 78 supported by supports 79 on the top of casing 66. Connected rigidly with the rock shaft is an arm 80 connected by a clevis 81 to the core 82 of a solenoid 83. A weight 84 is fixed to the outer end of arm 80. The solenoid is connected in parallel, by wires 85 with the leads 86 of the electric motor 68 which drives the fan, circuit 85 containing suitable resistance 87. In case the mill stops, back firing through the nozzle and fan into the mill is a possibility and might produce a destructive explosion in the mill. This possibility is forestalled by the apparatus just described. When the fan is stopped by shutting off current to its driving motor 68, current is simultaneously shut off from solenoid 83 which is deenergized and drops its core. Weight 84 rocks the crank structure 80, 78, 77, so that the latch end of the structure 77 is disengaged from the finger 76 of lever 74 and the weight 75 causes the lever to drop, thereby moving valve 73 to its closing position.

Summary of operation.—The feed of coal to the mill C through feeder D is controlled by operation of the variable speed transmission (Fig. 4). Simultaneously dampers 46, 47 are shifted, automatically, to increase or decrease the air supply to the mill. The coal, when pulverized sufficiently to be raised by the air lift created by fan F, is drawn up through pipe E into the fan and passes from the fan through casings 66 and 65 to the multiple burner B, the single stream being divided vertically into three streams by vanes 70. Auxiliary air is drawn into each burner nozzle through pipe 64 forming a central air core within the stream of primary air and fuel which brings about diminution of the velocity of the burner flames. In case of stoppage of the fan E valve 73 is dropped through deenergization of solenoid 83 to prevent back firing into the mill. Valve 73 may be re-set by hand when the mill is started up.

While I have described my invention in a preferred embodiment comprising several features intending to be used in combination, it is realized that some of these features would have utility when used in other situations and that it is not essential that all of the features shown be combined in a single installation. As to details of construction and arrangement, modifications might be made without departure from the principles of the invention. Therefore I intend to cover by patent all features of novelty within the scope of the appended claims.

I claim:

1. In combination with a furnace for burning pulverized fuel, a pulverizing mill operating at a constant speed, means for introducing fuel into the mill in variable quanti-

ties, mechanism for introducing air into the mill to carry out the pulverized fuel and transport the same to the furnace, and means for automatically controlling the introduction of air to maintain an approximately constant ratio between air and fuel, and a burner for the introduction of the fuel stream into the furnace provided with a duct through which auxiliary air enters the furnace with said fuel stream.

2. In combination with a furnace for burning pulverized fuel, a pulverizing mill operating at a constant speed, means for introducing fuel into the mill in variable quantities, mechanism for introducing air into the mill to carry out the pulverized fuel and transport the same to the furnace, means for automatically controlling the introduction of air to maintain an approximately constant ratio between air and fuel, and a burner for the introduction of the fuel stream into the furnace provided with a duct through which auxiliary air is drawn into the furnace with the fuel stream by induction.

3. In combination with a furnace for burning pulverized fuel, a pulverizing mill operating at a constant speed, means for introducing fuel into the mill in variable quantities, mechanism for introducing air into the mill to carry out the pulverized fuel and transport the same to the furnace, means for automatically controlling the introduction of air to maintain an approximately constant ratio between air and fuel, and a burner for the introduction of the fuel stream into the furnace provided with a centrally arranged auxiliary air conduit.

4. In combination with a furnace for burning pulverized fuel, a pulverizing mill operating at a constant speed, means for introducing fuel into the mill in variable quantities, mechanism for introducing air into the mill to carry out the pulverized fuel and transport the same to the furnace, means for automatically controlling the introduction of air to maintain an approximately constant ratio between air and fuel, and a burner for the introduction of the fuel stream into the furnace provided with a centrally arranged auxiliary air conduit through which air is drawn into the furnace by induction.

5. The combination with a furnace for burning pulverized fuel, a mill for pulverizing the fuel, a conduit, and means for propelling the fuel in suspension in an air current through the conduit directly from the mill to the furnace; of means operative automatically when the fuel propelling means is de-energized for shutting off communication between the furnace and the mill.

6. The combination with a furnace for burning pulverized fuel, a mill for pulverizing the fuel, a conduit, and means for propelling fuel in suspension in an air current through said conduit directly from the mill

to the furnace; of a valve in said conduit, means which normally holds said valve in a non-obstructing position, and mechanism actuated automatically when the fuel propelling means is de-energized for releasing the valve so that it falls to a position to close communication between the furnace and mill.

7. The combination with a furnace for burning pulverized fuel, a mill for pulverizing said fuel, a conduit through which fuel is carried in suspension in an air current directly from the mill to the furnace, means for propelling the fuel through the conduit, and an electric motor for driving the propelling means; of mechanism actuated when current is shut off from the motor for closing communication from the furnace to the mill.

10 8. The combination with a furnace for burning pulverized fuel, a pulverizing mill, a conduit through which fuel is carried in suspension in an air current directly from the mill to the furnace, means for propelling the fuel through the conduit, and an electric motor for driving the propelling means; of a valve adapted to close communication between the furnace and the mill, means to automatically close the valve, and releasable mechanism comprising an electro-magnet energized and de-energized when the current is supplied and shut off from the motor for holding said valve in an unobstructing position when the mill is operating and for releasing the valve so that the closing means will move it to closed position when the mill is stopped.

9. The combination with a furnace for burning pulverized fuel, a pulverizing mill, a conduit through which fuel is carried in suspension in an air current directly from the mill to the furnace, means for propelling the fuel through the conduit, and an electric motor for driving the propelling means; of a valve adapted to close communication between the furnace and mill, a solenoid energized and deenergized when current is supplied to or shut off from the motor, a latch connected with the solenoid core for supporting said valve in an unobstructing position when the solenoid is energized, and means for releasing the valve from said latch when said solenoid is deenergized.

10. In combination, a furnace for burning pulverized fuel, a pulverizing mill, a conduit and blower for withdrawing air and pulverized fuel from the mill and introducing the same into the furnace, an electric motor for driving said blower, a valve in said

conduit provided with a rock shaft, a weighted arm on said rock shaft, a solenoid energized and deenergized when said motor is supplied with and deprived of current respectively, a weighted lever pivoted to the solenoid core provided with a lever engageable with the arm on said rock shaft when the solenoid is energized and adapted to be disengaged from said arm when the solenoid is deenergized.

11. In combination with a furnace for burning pulverized fuel, a conduit leading to the furnace through which pulverized fuel is transported to the furnace in suspension in an air current, a blower to produce the air current, means for operating the blower, a valve in said conduit normally in an unobstructing position, and means whereby when the blower-operating means is de-energized, said valve is automatically moved to a position to close said conduit.

12. The combination of a furnace for burning pulverized fuel, a conduit leading to said furnace, means for transporting pulverized fuel in suspension in an air current through said conduit to the furnace, said means comprising an electric motor, a valve normally held in an unobstructing position and adapted to be released to obstruct the passageway through said conduit, and means for holding said valve in its unobstructing position comprising an electro-magnet energized and deenergized when said electric motor is supplied with and deprived of current, respectively.

13. In combination with a furnace, a conduit leading thereto through which pulverized coal is supplied to the furnace, a valve in said conduit, a latch for holding said valve in an unobstructing position, a solenoid having a core to which said latch is pivoted, and means whereby when the solenoid is deenergized the valve is released from said latch.

14. In combination, a furnace, a pulverizing mill having an air intake, means for feeding fuel in variable quantities into the pulverizing mill, means for controlling the introduction of air into the mill through said intake proportionately to the introduction of fuel, a conduit leading from the mill to the furnace, a fan in said conduit, means for rotating the fan, a valve, normally in unobstructing position in said conduit and means which automatically operate to cause the valve to move to an obstructing position when the fan-rotating means is de-energized.

LARS H. BERGMAN.

Certificate of Correction.

It is hereby certified that in Letters Patent No. 1,568,945, granted January 5, 1926, upon the application of Lars H. Bergman, of Chicago, Illinois, for an improvement in "Apparatus for Pulverizing and Feeding Fuel to Furnaces," an error appears in the printed specification requiring correction as follows: Page 4, line 46, claim 9, after the word "mill" insert the words *means for automatically closing the valve*; and that the said Letters Patent should be read with this correction therein that the same may conform to the record of the case in the Patent Office.

Signed and sealed this 2d day of February, A. D. 1926.

[SEAL.]

WM. A. KINNAN,
Acting Commissioner of Patents.
